POST MITT FOR CHAIRS AND OTHER
FURNITURE

John B. Mince, Fort Payne, Ala.

Application December 28, 1951, Serial No. 17,843

Term of patent 14 years

(Cl. D15—1)

To all whom it may concern:

Be it known that I, John B. Mince, a citizen of the United States, residing at Fort Payne, county of De Kalb and State of Alabama, have invented a new, original, and ornamental Design for Post Mitt for Chairs and Other Furniture, of which the following is a specification, reference being had to the accompanying drawing, forming a part hereof.

Figure 1 is a perspective view of a post mitt for chairs and other furniture, showing my new design, the broken lines representing a leg of an article of furniture for illustrative purposes only, and

Figure 2 is a top plan view of the furniture post mitt of my design.

I claim:

The ornamental design for a post mitt for chairs and other furniture, as shown and described.

JOHN B. MINCE.
